(57) **CLAIM**

The ornamental design for an actuator, as shown and described.

DESCRIPTION

FIG. 1 illustrates a right side view of the actuator showing my new design;

FIG. 2 illustrates a front elevated view thereof;

FIG. 3 illustrates a rear elevated view thereof;

FIG. 4 illustrates a top view thereof;

FIG. 5 illustrates a bottom view thereof;

FIG. 6 illustrates a left side view thereof;

FIG. 7 illustrates a rear perspective view thereof;

FIG. 8 illustrates a front perspective view thereof; and,

FIG. 9 illustrates a front perspective view thereof, shown in environmental use.

The broken lines shown represent unclaimed subject matter and form no part of the claimed design.
